UNITED STATES PATENT OFFICE

2,082,906

COILING MACHINE

Willie E. Risinger, Minneapolis, Minn.

Application August 17, 1935, Serial No. 36,715

4 Claims. (Cl. 1—40)

This invention relates to coiling machines and has special reference to one adapted for use in forming coils of metal wire or the like.

The principal object is to produce a simple and conveniently operated and adjustable machine of this type whereby to form rings of one or more coils as desired.

Another object is to produce such a machine readily adjustable to accommodate the requirements of various types of work.

Still another object is to produce such a machine in which coils of any desired number of convolutions may be formed directly through or within perforations in one or more sheets of paper or the like, as in loose leaf books, tablets, or the like, and which coils are automatically severed at the conclusion of their formation.

Other objects and advantages of the invention will appear in the following description thereof.

Referring now to the accompanying drawing, forming part of this application, and wherein like reference characters indicate like parts:

Figure 1 is an isometric perspective view of one of the completely assembled coiling machines.

Figure 2 is a similar view of the control mechanism for the cutting of the coils from the stock after being formed, and which mechanism is mounted on the backside of the machine, as appears in Figure 1.

Figure 3 is a perspective view of one form of mandrel about which the coil is formed.

In the embodiment of the coiler here illustrated I have shown the supporting mechanism as comprising a bed plate portion 1, an upright portion 2, and a horizontally extending beam 3, which is directly above and parallel with, though spaced from, the main portion of the bed plate 1, and these parts may or may not be integrally formed as desired. Rotatively mounted upon the back side of the upright or standard portion 2 of the support is the driving gear wheel 4, and back of which on the same pivotal support or shaft, though free to operate independently of the wheel 4, is the cross arm 5, it being pivotally attached at its lower end as at 6 to the power supply reciprocal pitman 7, the latter's connection to any desired form of rotating power means not being illustrated, as the lower end of the cross arm 5 is simply designed to be operated back and forth in the lowermost arc of the wheel. At the upper end of the cross arm 5 is pivotally mounted as at 8 the pawl 9 which

any two teeth of the gear 4 by means of a suitable spring illustrated at 10, so that reciprocal action of the lower end of the cross arm 5 will intermittently rotate the gear 4 in anti-clockwise direction, as here viewed.

The teeth of the gear 4 not only function in conjunction with the pawl 9 and arm 5 through which it receives its power, but is in constant mesh with the small spur gear 11 mounted upon a shaft 12 journalled within the beam 3. This shaft 12 also carries on the same side of the beam 3 as the gear 11 a somewhat larger gear 13 which is in constant mesh with a like gear 14 on the shaft 15 also but indirectly journalled in the beam 3 and parallel with the shaft 12, so that the shafts 12 and 15 are rotated in unison. Upon that portion of the shafts 12 and 15 extending forwardly of the beam 3 are mounted a pair of cooperative discs 16 and 17 respectively. These discs are grooved circumferentially, the depth of the groove being equal to slightly less than half the diameter of the wire being operated upon and from which the coils are to be formed, and the wire is designed to be fed intermediate of these discs as clearly illustrated and forced downwardly by the rotation of the same; the disc 16 being operated in clockwise direction and the one 17 in anti-clockwise direction, as their respective shafts are rotated with the action of the gears 13 and 14, previously described.

The wire is illustrated at 20 and is fed from any suitable source through the guiding member 21 to and intermediate of the circumferential faces of the discs, and from thence into the upstanding tubular guide 22 carried upon the coiler head 23, the latter being a suitable metal block either integral or otherwise fixed to the upper face of the bed 1, and is provided with a bore or core transverse same as well as the axes of the shafts 12 and 15 for the reception of, as here illustrated, the mandrel 24. This mandrel is shown more in detail in Figure 3 of the drawing and has a cutout channel or slot illustrated at 25 the full length thereof for the reception of any work or object in which it is desired to form the coils or rings and it is understood that the rearmost edge of the bore of the coiler head is in direct alignment with the hole through which the wire 20 is fed into the head the full size of the wire being received into said bore and about a groove 26 here shown as formed adjacent one extreme end of the mandrel 24; this being the construction of mandrel best adapted for forming the rings or coils in a single hole or slot as demanded by the work being operated

upon. The mandrel 24 is firmly held in position with the head by any suitable form of set screw as indicated at 27 and the slot 25 in said mandrel registers with a like slot 28 in the head 5 so that perforated work, for example a loose leaf tablet or the like of any width, may be operated upon in forming the rings directly within the perforations therein. It is apparent that when a forward stroke of the pitman 7 rotates the gear 10 wheel 4 a predetermined distance, the discs 16 and 17 will by friction force the wire downwardly through the guide 22 and the hole in the head into and around the lower portion of the groove 26 about the end of the mandrel 24, and as the 15 end of the wire comes upwardly into and passes the slot 25 it will be guided axially of the mandrel outwardly and away from the face of the head block 23 the thickness of itself by proper spacing of the uppermost corner of the slot 25 20 as at 29 so that the coil will continue to be uniformly shaped any desired number of convolutions; it being understood that the work for which the machine here illustrated is intended ordinarily requires a ring having three or more 25 coils, only one of which in any event remains in the block to be severed.

Now, appears the problem of severing the ring thus formed from the stock of which it is formed, and the same is accomplished automatically in 30 the following manner.

Within the back of the bed 1 is slidably mounted the bar 30, it having pivotally attached to the innermost end thereof, as at 31, the finger catch 32, this latter being normally held upwardly 35 against the pin 33 by the spring 34 on the pin 35, as both of these pins 33 and 35 are attached to the back face of the bed 1, just as the pin 36 is also fixed. Here it will be noted that a similarly shaped pin 37 is carried on the end of the 40 cross arm 5 and outwardly of the gear 4, though extended inwardly towards the bed 1 of the device, and as the pitman 7 swings the lower end of the cross arm 5 to the opposite limit of its stroke to that shown in Figure 1 of the drawing 45 this pin 37 will engage the arcuate lip 38 of the finger 32 and become engaged back of the notch 39 formed therein so that when the lower end of the cross arm 5 idly returns for another stroke the finger 32 will be drawn with it a predetermined distance, the termination of which is governed by the position of the pin 36 on the back wall of the bed 1, it being apparent that as the 50 arcuate lip 38 of the finger engages said pin it will depress the free end of the finger and disengage it from the draft pin 37, and as the bar 30 is normally held in retracted position by the spring 40 fixed intermediate the end thereof and the bracket 41 it will instantly return to its former position ready for another engagement by the pin 37 at a subsequent stroke of the machine. Now when this reciprocal motion of the 55 bar 30 takes place it is designed to intermittently operate the knife or cutting bar 42 which is slidably mounted within and longitudinally of the head 23 and beneath the mandrel bore. This operation is accomplished by the rearmost end of the bar 42 carrying a roller 43 depending therefrom, which roller is intermittently engaged by the cam 44 fixed to the rearmost edge of the 60 bar 30 so that when the bar 30 is pulled by the action of the pin 37 on the cross bar 5 as previously described it will draw the knife bar rear-

wardly and as this knife bar carries on its head 45 the knife 46 the cutting edge of which slides over the lower lip of the slot 28 in the head when the outermost corner of said knife will neatly sever the one remaining convolution of wire in 5 the mandrel and instantly return to its normal position as shown by the action of any form of expansive spring 47.

When this is accomplished it is evident that the tablet, calendar, or whatever the work may 10 be, will have, for example, the first of the rings applied thereto, when it may be slid to the other unoccupied perforations through which a ring may be selectively formed.

In order that suitable frictional contact with 15 the wire may be had I have mounted the shaft 15 in the cross head 48 within a suitable slot 49 in the extreme end of the beam 3 engaged by an expansive helical spring 50 adjustable by means of the set screw 51 so that this shaft 15 is susceptible of slight movement and adjustment to cause the proper impingement of the wire by the discs 16 and 17, and this without any injurious effects in respect to the meshing of the gears 13 and 14. 25

Having thus described my invention, what I claim and desire to secure by Letters Patent, is:

1. In a device for forming a wire ring within a hole through a pad of paper, a driving gear wheel, means for intermittently operating said 30 driving wheel, a pair of gears driven by said driving gear, a pair of grooved discs operable by said gears, a mandrel having a grooved end to receive a wire forced longitudinally by said discs about the grooved mandrel, and cutting means for 35 severing the wire at the conclusion of a predetermined number of turns.

2. In a device for forming a wire ring within a hole through a pad of paper, a driving gear, a pair of grooved discs driven by said driving gear, 40 a mandrel having a grooved end and a longitudinal slot therein for reception of the pad of paper, said groove being for reception of a wire forced longitudinally by said discs about the grooved mandrel and through the hole in the 45 pad of paper, and cutting means for severing the wire at the conclusion of a predetermined number of turns.

3. A mandrel for a mechanism for forming a wire ring consisting of a plurality of turns of wire, 50 comprising a cylindrically shaped body portion having a channel in one side thereof its entire length, and a groove about the circumferential edge of one end thereof for guiding wire in a circular course and away from said mandrel. 55

4. In a device for forming wire rings, a head block, an adjustable cylindrical mandrel having a channel longitudinally disposed in one side thereof, a channel within the adjacent end of said head block for registration with the channel 60 in the mandrel, a spirally shaped groove about the ring forming end of said mandrel, that portion of said groove opposite said channel in the mandrel registering with a vertically disposed hole accessible from the upper surface of said block, means for forcing ring forming wire into and through said hole in the head block, around the end and away from said mandrel, and means for severing said wire after a ring having a predetermined 65 number of coils is formed. 70

WILLIE E. RISINGER.
